STORAGE RACK

Donald N. Schendel, 2906 S. 116th Ave.,
Omaha 44, Nebr.

Filed Apr. 30, 1965, Ser. No. 85,039

Term of patent 14 years

(Cl. D80—9)

I claim:

The ornamental design for a "storage rack," as shown and described.
